COLUMN

George B. Coubrough, Long Beach, Calif., assignor to The Lummus Company, New York, N. Y., a corporation of Delaware

Application July 13, 1932, Serial No. 622,209

4 Claims. (Cl. 202—158)

The present invention relates to columns and more particularly to distilling and rectifying columns in which provision is made for obtaining intermediate or side products.

5 In one form of column now in use, a stripping section for intermediate products is arranged in an annular space adjacent the inside wall of the column, the center portion of the column being used as a vapor passage. In such a column, the 10 stripping section takes up a large proportion of the cross-sectional area of the column, thereby restricting the central vapor passage. The vapor passage is necessarily of relatively small cross-section and cannot be increased beyond a certain 15 limit without restricting the stripping section to such a narrow annular space that an unfavorable distribution of liquid results. Moreover, the central vapor passage takes up space in the column without serving any purpose other than a conduit.

20 The principal object of the present invention is to provide a column having a stripping section so disposed as to provide ample space for passage of the vapors and also to make use of the vapor passage for accommodating entrainment separators or the like. To this end, the present invention consists in the column hereinafter described and particularly defined in the claims.

25 In the accompanying drawing, Fig. 1 is a diagrammatic elevation of the preferred form of column; Fig. 2 is a section on line 2—2 of Fig. 1; and Fig. 3 is a section on line 3—3 of Fig. 1.

The preferred form of column, as shown in the drawing, comprises a shell 4 having contact means arranged in several stages and illustrated as the 30 boiling cap decks 6. Between stages of boiling cap decks is located an intermediate stripping column 8 which comprises a shell disposed centrally of the main column. This stripping column is provided with boiling cap decks 10. The upper 35 part of the shell 8 is joined to the lowermost deck of the rectifying stage immediately above.

40 Down pipes 12 are employed to convey reflux from deck to deck. Down pipes 14 are also employed to convey reflux downwardly into the central stripping column. It will be noted that there is no passage for reflux liquid from the lowermost deck of any rectifying stage except into the stripping section. A down pipe 16 leads from the bottom of the stripping section to the uppermost 45 deck of the rectifying stage next below. Steam is admitted to the rectifying section through a pipe 18. A side product may be withdrawn from the stripping column through a draw-off 50 having a valve 22. The opening of the valve 22 determines the amount of liquid drawn off and

hence determines the proportion returned to the rectifying stage immediately below the stripping column.

The stripping column is internally supported from the shell 4 by means of inclined struts 24 secured at their inner ends to the shell 8 and at their outer ends upon annular ledges 26 attached to the inner wall of the main shell. These struts are used to support entrainment separators which consist of a series of annular overlapping baffles 10 28. As shown in Fig. 1, each baffle is mounted between adjacent struts, being supported on angles 30 welded to the struts. At its outer edge, each baffle is formed with a hook-like lip 32 forming a trough to convey entrainment toward 15 the struts. Beneath each strut is supported a channel member 34 serving to convey entrainment downwardly toward the wall of the main shell.

20 In operation of the column, the vapors pass through the lowermost rectifying stage and then around the central stripping column into the rectifying stage next above. The vapors in their passage through any rectifying stage are contacted with downwardly flowing reflux which 25 eventually passes into the central stripping column. Any remnant of lighter materials present in the reflux is stripped therefrom by steam introduced through the pipe 18, leaving in the bottom of the stripping column a material intermediate to the final vapors and the main residue. 30

35 The vapors in their passage around the stripping section are deflected outwardly by the entrainment catching baffles. The change in the direction of the vapors effectively throws off any entrainment, some of which is caught in the troughs at the edges thereof. The entrainment thus caught flows toward the struts and either runs down the struts or drops into the channels 34 by which means it is carried to the inside wall 40 of the main column. The entrainment falling down the inside wall is therefore not permitted to be carried upwardly again in the vapor stream.

45 By this construction, the entrainment separators are conveniently disposed in the annular space surrounding the stripping column, which space would otherwise be of no value. The use of such entrainment separators permits a reduction in the number of decks required in any rectifying stage, the decks being then used only 50 for their intended purpose of rectification without being required to assume any of the duty of entrainment separation. Accordingly, by the elimination of some boiling cap decks, the cost of the material is greatly reduced particularly since 55

the overall height of the column may be no greater than that of an ordinary column without the stripping section.

5 The stripping column is necessarily of only small diameter since the quantity of vapors formed therein is small in comparison to the total vapors passing through the main column. Accordingly, the annular space surrounding the stripping column is sufficiently large to accommodate the full volume of vapors. Since the decks in the stripping column are of regular circular shape, they present no problem of liquid distribution, such as may occur with annular decks.

10 15 Having thus described the invention, what is claimed is:

1. The combination with a main column having contact means, of an internal stripping column, means for supporting the stripping column from the walls of the main column to provide an annular vapor passage around the stripping column, and overlapping entrainment catching baffles 20 traversing said passage.

2. The combination with a main column having contact means, of an internal stripping column, 25 means for supporting the stripping column from

the walls of the main column to provide an annular vapor passage around the stripping column, including inclined struts, and annular overlapping entrainment catching baffles on the struts.

3. The combination with a main column having contact means, of an internal stripping column, means for supporting the stripping column from the walls of the main column to provide an annular vapor passage around the stripping column, including struts inclined downwardly from the 10 stripping column to the main column, annular overlapping entrainment catching baffles on the struts, and a channel below each strut to convey entrainment to the walls of the main column.

4. The combination with a main column having contact means, of an internal stripping column, means for supporting the stripping column from the walls of the main column to provide an annular vapor passage around the stripping column including struts inclined downwardly from the 20 stripping column to the main column, and annular overlapping entrainment catching plates on the struts, each plate having an outer lip to convey entrainment to the struts, along which it passes to the wall of the main column.
